Primary Examiner — Marianne Pandozzi(74) *Attorney, Agent, or Firm* — Polsinelli PC**CLAIM**

The ornamental design of the drink bottle with smooth hand grip, as shown and described.

DESCRIPTION

FIG. 1 is a perspective view taken from the upper, front, right-hand side of the drink bottle with smooth hand grip of the present invention;

FIG. 2 is a perspective view taken from the lower, rear, left-hand side of the drink bottle with smooth hand grip of FIG. 1; FIG. 3 is a side elevational view of the left side of the drink bottle with smooth hand grip of FIG. 1;

FIG. 4 is a front elevational view of the drink bottle with smooth hand grip of FIG. 1;

FIG. 5 is a side elevational view of the right side of the drink bottle with smooth hand grip of FIG. 1;

FIG. 6 is a rear elevational view of the drink bottle with smooth hand grip of FIG. 1;

FIG. 7 is an enlarged top plan view of the drink bottle with smooth hand grip of FIG. 1; and,

FIG. 8 is an enlarged bottom plan view of the drink bottle with smooth hand grip of FIG. 1.
